[57] CLAIM

The ornamental design for a computer mouse, as shown and described.

DESCRIPTION

FIG. 1 is a top, front, right perspective view of a computer mouse showing my new design, on a reduced scale;

FIG. 2 is a top plan view thereof;

FIG. 3 is a front elevational view thereof;

FIG. 4 is a left-side elevational view thereof;

FIG. 5 is a rear-elevational view thereof;

FIG. 6 is a right-side elevational view thereof;

FIG. 7 is a bottom plan view thereof;

FIG. 8 is a top, rear, left perspective view thereof, on a reduced scale; and,

FIG. 9 is a top, front, left perspective view of a second embodiment thereof, on a reduced scale, the second embodiment is similar to the original embodiment except that it is a mirror image.

FIG. 2.

FIG. 1.

FIG. 3.

FIG. 5.

FIG. 4.

FIG. 6.

FIG. 7.

FIG. 8.

FIG. 9.
